CLAIM

The ornamental design for a rocking chair, as shown and described.

DESCRIPTION

FIG. 1 a left front perspective view of a rocking chair showing my design;

FIG. 2 is a right side elevation view of a rocking chair showing my new design, the opposite side being a mirrored image thereof;

FIG. 3 is a top elevation view looking down thereof;

FIG. 4 is a bottom elevation looking up thereof;

FIG. 5 is a front elevation view thereof; and,

FIG. 6 is a rear elevation view thereof.
